UNITED STATES PATENT OFFICE.

ADOLF CONVERT, OF NEW YORK, N. Y., ASSIGNOR TO THE AMERICAN CARBONATE COMPANY, OF SAME PLACE.

STOP-COCK.

SPECIFICATION forming part of Letters Patent No. 368,073, dated August 9, 1887.

Application filed April 14, 1887. Serial No. 234,790. (No model.)

To all whom it may concern:

Be it known that I, ADOLF CONVERT, a subject of the Emperor of Germany, residing at New York, in the county and State of New York, have invented new and useful Improvements in Stop-Cocks, of which the following is a specification.

The object of this invention is a stop-cock which can be used with advantage for liquids or fluids under a very high pressure—such, for instance, as liquid carbonic acid.

The peculiar and novel construction of my stop-cock is pointed out in the following specification and claim, and illustrated in the accompanying drawings, in which—

Figure 1 represents a longitudinal section. Fig. 2 is a transverse section in the plane xx , Fig. 1.

Similar letters indicate corresponding parts. In the drawings, the letter A designates the middle section of the shell of my stop-cock. B is the lower section of said shell, and C is its top section. The lower section, B, is provided with a screw-nipple, a, by means of which it can be connected to the fountain, which contains liquid carbonic acid, or any other fluid under a high pressure. Said lower section is provided at its top with a screw-socket to engage with a screw-thread, b, at the lower end of the middle section, A, and said middle section is provided at its upper end with a screw-socket to engage with a screw-thread, c, at the lower end of the top section, C. The upper end of this top section forms a stuffing-box, d, through which extends the screw-spindle D, the screw-thread of which engages with a female thread, e, in the interior of the lower portion of the top section, C.

E is the valve-stem, which is provided at its upper end with a center point, f, to engage with a cavity, g, in the inner end of the screw-spindle, and on which is formed a flange, h, which rests in a screw-cap, i, the screw-thread of which engages with a screw-thread, j, on the screw-spindle D, and which, when screwed up tight, bears against a flange, K, on said screw-spindle, allowing the valve-stem E a certain freedom of motion. Said valve-stem carries two valves, l m, the valve l being situated above the delivery-channel n, while the valve m is situated below said delivery-channel.

In the interior of the middle section, A, of the shell are formed two valve-seats, o p—

one for the valve l and the other for the valve m—and the position of these valve-seats is so adjusted that when the screw-spindle D is screwed down to the position shown in Fig. 1 the valve l will be firmly closed while the valve m is opened, so as to allow the liquid from the fountain to escape through the delivery-channel n, while the escape of the liquid through the upper portion of the shell is effectively prevented. When the screw-spindle is turned up, the valve m closes and the valve l opens. In order to facilitate the adjustment of the valves, the valve-seats o p are made of vulcanized rubber or other elastic material.

By providing the valve-stem with the flange h, located inside of the cap i, which is screwed upon the screw-spindle, a novel loose connection is provided between the stem carrying the two valves and the screw-spindle, so that both valves l m are enabled to adjust themselves in their seats, so as to close tight, which is of great importance in dealing with liquids or fluids under such a high pressure as ten hundred pounds to the square inch, such being the pressure under which liquid carbonic acid has to be kept in order to retain the same in its liquid form.

What I claim as new, and desire to secure by Letters Patent, is—

The combination, in a stop-cock, of the upper and lower sections, B C, the middle section, A, having the delivery-channel n, and provided, respectively, above and below the channel with the valve-seats o p, and the spindle D, screw-threaded in the upper section and provided at its lower end with a screw-thread, j, the screw-cap i, engaging the latter, and the valve-stem E, having at its upper end a flange, h, loosely confined between the screw-cap and the screw-spindle and provided with two valves, l m, one arranged in the middle section above its valve-seat and the delivery-channel and the other arranged in the lower section below its valve-seat and the said delivery-channel, substantially as described.

In testimony whereof I have hereunto set my hand and seal in the presence of two subscribing witnesses.

ADOLF CONVERT. [L. S.]
